**CORNER MOUNTING DEVICE FOR SHEAVES
AND THE LIKE**

Mentor C. Addicks, Minneapolis, Minn.

Application October 26, 1953, Serial No. 388,116

22 Claims. (Cl. 248—216)

My invention relates generally to anchoring devices, and more specifically to releasable anchoring devices adapted to be mounted diagonally across inside corners of an enclosure.

In the emptying of large containers or enclosures such as railroad boxcars, bins, ship holds and the like, of granular bulk material, such as grain, unloading mechanism including power operated scoop or shovel is generally used. Such mechanism usually involves one or more power operated winding drums, cable wound thereon, and a scoop or shovel attached to the cable. Some such machines require that the scoop be manually removed to a point remote from the place of discharge, after which the scoop is drawn to the place of discharge with a load of material by winding of the cable upon the drum under power. In other instances, the unloading mechanism moves the scoop in both forward unloading and return directions. Such a machine is disclosed and claimed in my prior United States Letters Patent 2,646,965. This type of automatic shovel machine requires that a tail sheave or pulley be firmly anchored at a suitable location remote from the point of delivery, so that the return cable may run thereover. Heretofore, the tail sheave has been secured to a hook driven into an end wall of the enclosure or to a plate secured to said end wall by nails or the like. Other means for supporting the tail sheave has included a relatively heavy beam extending the entire width of the enclosure and nailed or otherwise rigidly secured to the opposite side walls thereof. These devices have proved unsatisfactory in that, pulleys secured to the end wall often work loose and become detached therefrom, and in the case of anchoring beams extending across the width of the enclosure, valuable time and effort is consumed in the proper mounting of said beams. Moreover, when material is to be removed from a bin or car of considerable height, the anchoring device is generally placed above the top of the grain near the top wall of the enclosure at the beginning of the unloading operation, and after a substantial quantity of the material has been removed, it is desired that the tail sheave be also lowered to obtain the most efficient operating conditions.

An important object of my invention is the provision of a tail sheave mounting device for a machine of the type above described which may be quickly and easily anchored to adjacent inside corner forming walls of an enclosure, and which may be as readily removed therefrom when desired.

Another object of my invention is the provision of a mounting device which may be placed diagonally across an inside corner of an enclosure, and which is provided with gripping teeth which are movable with respect relative to each other and which are adapted to engage and penetrate the walls of the enclosure whereby to firmly support a tail sheave.

Still another object of my invention is the provision of an anchoring device as set forth which comprises a co-operating pair of gripping tooth-equipped bar elements

2

which are movable relative to each other to produce shortening and elongation of the device, whereby to cause the teeth thereon to engage and penetrate adjacent inside corner forming wall portions of an enclosure upon relative movements of said bar elements in a direction to cause elongation of the device.

A still further object of my invention is the provision of an anchoring device as set forth in which one of the gripping teeth thereof is extendible and retractible longitudinally of the device and wherein novel means is provided whereby when a load is applied to a pulley carried by the device, said load will cause the teeth to penetrate further into the walls of the enclosure.

Still another object of my invention is the provision of a tail sheave anchoring device as set forth which is relatively simple and inexpensive to manufacture, which is highly efficient in operation, which is relatively light in weight, and which is rugged in construction and extremely durable in use.

The above, and still further highly important objects and advantages will become apparent from the following detailed specification, appended claims and attached drawings.

Referring to the drawings, which illustrate the invention, and in which like characters indicate like parts throughout the several views:

Fig. 1 is a fragmentary view partly in plan and partly in horizontal section of a conventional railway car illustrating the use of a preferred form of my invention;

Fig. 2 is a view corresponding to a portion of Fig. 1 on an enlarged scale, some parts being broken away and some parts being shown in section, and illustrating a different position of some of the parts;

Fig. 3 is a view corresponding to Fig. 2 but showing the parts in the position of Fig. 1;

Fig. 4 is a view in side elevation of the invention of Figs. 1 to 3 inclusive as seen from the line 4—4 of Fig. 3, some parts being removed and some parts broken away;

Fig. 5 is an enlarged transverse section taken substantially on the line 5—5 of Fig. 4, some parts being broken away;

Fig. 6 is a view in end elevation of one of the gripping teeth of my invention illustrated in Figs. 1 to 4 inclusive;

Fig. 7 is a view in end elevation of the other of the gripping teeth of Figs. 1 to 4 inclusive;

Fig. 8 is a view corresponding to Fig. 2 but showing a modified form of the invention;

Fig. 9 is a view corresponding to Fig. 8 but showing a different position of some of the parts;

Fig. 10 is a view in side elevation of the form of the invention illustrated in Figs. 8 and 9;

Fig. 11 is a view corresponding to Fig. 2 but showing a still further modified form of the invention;

Fig. 12 is a view corresponding to Fig. 11 but showing a different position of some of the parts;

Fig. 13 is an enlarged fragmentary detail partly in section and partly in side elevation, taken substantially on the line 13—13 of Fig. 12; and

Fig. 14 is an enlarged fragmentary detail partly in section and partly in side elevation, taken on the line 14—14 of Fig. 12.

Referring with greater detail to the drawings, and more particularly to the preferred embodiment of the invention illustrated in Figs. 1 to 7 inclusive, an enclosure in the nature of a conventional railway freight car is indicated in its entirety by the numeral 1 and comprises a bottom wall or floor 2, opposed side walls 3 and 4 and end walls 5, one of which is shown. As shown, the side wall 4 is provided with an opening 6 for the loading and unloading of material from the interior of the car 1. A pull-forward or unloading cable 7 runs over a suitable pulley 8 and

is attached at one end to an unloading shovel or scoop 9, and a pull-back or return cable 10 runs over a similar pulley 11 and a tail pulley or sheave 12, one end thereof being attached to the scoop 9 as indicated at 13. The opposite ends of the cables 7 and 10 may be assumed to be wound upon suitable power driven winding drums as fully set forth in my prior Patent 2,646,965, and the pulleys 8 and 11 may be assumed to be suitably mounted on a loading dock structure or the like not shown.

For the purpose of anchoring the tail sheave 12, I provide an anchoring device 14 comprising a bar element 15 and a cooperating second bar element 16 that is pivotally secured adjacent its outer end 17 to the inner end portion of the first bar element 15 as indicated at 18. The bar element 15 is provided intermediate its ends with a depending handle 19 by means of which the device may be held while being placed in position diagonally across the inside corner defined by the angularly disposed walls 3 and 5 of the car 1. The second bar element 16 is provided with a handle member 20 whereby the bar element 16 may be pivotally moved from its angularly disposed position of Fig. 2 to a position generally parallel to the first bar element 15 as indicated in Fig. 3. As shown, movement between these positions produces shortening and elongation of the device as will hereinafter be described.

It will be noted that the bar element 15 is formed in the shape of a generally rectangular tube. Mounted for extending and retracting movements in the outer end portion of the bar element 15 is a third bar element 21a carrying a gripping tooth 21 having a relatively wide surface portion 22 at one side thereof and a sharp edge 23 in opposition to the surface 22. As clearly shown in Figs. 2 and 3, the surface 22 and the sharp edge 23 taper to a sharp point 24 at the outer end of the tooth 21. A pair of nut equipped bolts 25 extend transversely through the outer end portion of the bar element 15 in underlying relation to the third bar element 21a carrying the gripping tooth 21, and cooperate with internal wall surfaces of the bar element 15 to guide the tooth 21 in its extending and retracting movements. A lever 26 is pivotally secured to the gripping tooth 21 as indicated at 27, and extends laterally outwardly through a slot 28 in one side wall of the bar element 15. One end 29 of the slot 28 provides a fulcrum for the lever 26 the purpose of which will hereinafter become apparent.

Rigidly secured, by means of nut equipped bolts or the like 30 to the outer end of the second bar element 16 is a gripping tooth 31 having a relatively wide surface 32 and a sharp edge 33 opposed to the relatively wide surface 32. The surface 32 and edge 33 taper longitudinally outwardly to a relatively sharp point 34 at the outer end of the tooth 31. It will be noted that the tooth 31 differs from the tooth 21 in that the surface 32 and edge 33 of the tooth 31 define converging arcs, whereas the surface 22 and edge 23 of the tooth 21 are straight. It will also be noted particularly with reference to Fig. 2 that the tooth 21 is limited in its retracting movement in the bar element 15 by engagement with one side edge of the lever 26 with the outer end 35 of the slot 28.

When it is desired to mount the anchoring device in a suitable corner of the car 1, the operator places the device 14 as illustrated in Fig. 2, with the bar elements 15 and 16 in angularly disposed positions whereby to cause shortening of the device. The gripping teeth 21 and 31 are forced into the end and side walls 3 and 5 respectively after which the bar element 16 is moved into parallel relationship with the bar element 15 thereby causing elongation of the device and further penetration of the gripping teeth 21 and 31 into the wall portions respectively engaged thereby. The inner walls of boxcars and grain bins, preferably being made from wood, the teeth 21 and 31 penetrate the same with relative ease. A pulley mounting device comprises a flexible cable 36 and is secured at one end to the outer end of a lever 26, and

at its opposite end to a mounting lug 37 welded or otherwise secured to the outer end portion of the second bar element 16, and defines with said bar elements a closed loop. The tail sheave 12 is of the type in common use including a frame 12a and an eye or hook 12b which engages the cable 36. With reference particularly to Fig. 3 it will be seen that when the sheave 12 is under load or pulling strain of the cables 7 and 10, the lever 26 tends to swing about its fulcrum 29 and move the gripping tooth 21 in a longitudinally outwardly extending direction. This movement causes both gripping teeth 21 and 31 to penetrate further into the wall portions engaged thereby. Obviously, the greater the load exerted upon the cable 36, the greater will be the tendency for the gripping teeth to penetrate into the enclosure walls. It will be noted that the cable 36 is anchored sufficiently close to the outer ends of the bar elements 15 and 16 that there is little or no tendency for the bar elements 15 and 16 to be moved thereby out of parallel relationship when load is placed upon the cable. When it is desired to remove the anchoring device 14 from engagement with the walls 3 and 5, it is merely necessary that the cable 10 is slackened. Removal of the device is effected by swinging the second bar element 16 outwardly to its angular position of Fig. 2 at which time the tooth 31 may be withdrawn from the wall 3. Thereafter the tooth 21 is easily withdrawn from the wall 5.

In the modified form of the invention illustrated in Figs. 8 to 10 inclusive, a first bar element 38 comprises a pair of telescoping inner and outer sections 39 and 40. Pivotally mounted to the inner end of the element 38 as indicated at 41 is a second bar element 42 having rigidly secured to its outer end a gripping tooth 43 which is adapted to engage and penetrate the adjacent wall portion 5 when the bar element 38 is placed diagonally across the inside corner defined by the walls 3 and 5. A similar gripping tooth 44 is rigidly secured to the outer end of the third section 40 for common extending and retracting movements therewith longitudinally of the bar element 38. As shown in Figs. 8 and 9, movement of the bar element 42 from its angularly disposed position with respect to the bar element 38 to a position in parallel relationship with the bar element 38 causes elongation of the device and consequent penetration of the tooth elements 43 and 44 into their respectively engaged wall portions 5 and 3. In this form of the invention, the gripping teeth 43 and 44 are similar, each having flat sides 45 disposed opposite cooperating sharp edge portions 46, the relatively wide surfaces 45 and edges 46 converging outwardly and terminating in sharp points 47. In this form of the invention as in that illustrated in Figs. 1 to 7 inclusive, the relatively wide side surfaces of the gripping teeth face generally in the direction of the load imposed upon the device and reduce to a minimum the tendency of the engaged wall portions to splinter or otherwise give way under strain. The second bar element 42 at its inner end is provided with a handle 48 whereby said second bar element may be easily moved between its angularly disposed position relative to the first bar element 38 and its position parallel thereto. Preferably, this form of the invention is mounted in such a manner that the second bar element 42 swings in a horizontal plane. However, operation of the device is equally effective if the same is placed diagonally across an inside corner defined by a vertical wall and a horizontal top or bottom wall of an enclosure. Obviously, in this event, the bar element 42 would swing in a vertical plane. A toggle joint 49 comprises a pair of toggle links 50 and 51 pivotally secured together at their adjacent ends as indicated at 52. The free end of the toggle link 50 is pivotally mounted adjacent the inner end of the bar element 38, as indicated at 53, in spaced relation to the pivotal connection 41. The toggle link 51 likewise has its free end pivotally secured to the section 40 as indicated at 53' in closely spaced relation to the gripping

tooth 44. Preferably the toggle joint 49 moves in a horizontal plane or in a plane parallel to the plane of swinging movement of the bar element 42. Relative angular movement between the toggle links 50 and 51 imparts extending and retracting movements to the tooth equipped section 40. A drawbar 54 is provided at its opposite ends with loops or eyes 55 and 56 the former of which encompasses the pivot joint 52 of the toggle link 49, and the latter of which is adapted to have mounted thereon the tail sheave 12. The drawbar 54 extends transversely between the movable section 40 and a guide rail 57 which guide rail extends parallel to the bar element 38 and is formed to provide downturned ends 58 which are welded or otherwise rigidly secured to the movable section 40. The guide rail 57 permits lateral swinging movement of the drawbar 54 but restrains the same against swinging movement in a vertical plane or in a plane at right angles to the planes of swinging movement of the toggle joint 49 and the second bar element 42. As shown by full and dotted lines in Fig. 9, when the device has been suitably mounted to the walls 3 and 5, a load applied to the drawbar 54 will cause tooth extending movements to be imparted to the toggle joint 49. Obviously an increase in load on the drawbar 54 will cause increased penetration of the gripping teeth 43 and 44 into their respective walls 5 and 3. The arrangement in this form of the invention like that illustrated in Figs. 1 to 8 inclusive, is such that, when a load is applied to the drawbar 54, the tendency toward elongation of the device overcomes any tendency for the second bar element 42 to swing outwardly away from parallel relationship with the bar element 38. However, as a safety measure, I provide a hook element 59 that is secured at one end to the bar section 39 and which has a depending hook element 59' which is adapted to engage an outer edge portion of the bar element 42 to hold the same against accidental swinging movement away from said parallel relationship. Obviously, if desired, a similar hook arrangement may be applied to the preferred form of the invention illustrated to Figs. 1 to 7 inclusive.

In the modified form of the invention illustrated in Figs. 11 to 14 inclusive, a pair of bar elements 60 and 61 are connected for relative movements causing elongation and shortening of the device by a lazy tong arrangement comprising a pair of opposed toggle joints 62 and 63 the former of which includes toggle link 64 and a lever 65 and the latter of which includes a similar lever 66 and toggle link 67. Preferably and as shown, the free ends of the link 64 and lever 65 are pivotally secured to opposite ends of the bar element 60 as indicated at 68 and 69 respectively whereas the free ends of the lever 66 and link 67 are pivotally secured to opposite ends of the bar element 61 as indicated at 70 and 71 respectively. A rigid link 72 is pivotally secured at one end to the pivotal connection 73 between the link 64 and lever 65, and at its other end to the lever 66 as indicated at 74. A second link 75 is similarly pivotally secured at one end to the pivotal connection 76 between the lever 66 and toggle link 67 and at its other end to the lever 65 as indicated at 77. The links 72 and 75 transfer movements of one of the toggle joints 62 or 63 to the other thereof so that during relative movements between the bar elements 60 and 61, said bar elements are maintained in substantially parallel arrangement.

Means for imparting movements to the toggle joints 62 and 63 to cause elongation or shortening of the device comprises a threaded shaft 78 that has screw threaded engagement with a nut-acting element 79 which forms the pivotal connection 76. The shaft 78 is journaled in a boss 80 which forms a part of the pivotal connection 73 and which supports the generally U-shaped bearing 81. The outer end portion 82 of the shaft 78 is journaled in the bearing or yoke 81 and has mounted thereon a bevel gear 83 which has meshing engagement with a second bevel gear 84 mounted on a short shaft 85 that is

journaled in a bearing boss 86 on the intermediate portion of the yoke 81. At its lower end, the shaft 85 is provided with a cross sectionally polygonal head 87 which is engageable by a suitable socket wrench or the like shown by dotted lines in Fig. 13 and indicated at 88.

A pair of plate-like third bar members 89 and 90 are hinged one each to a respective bar element 60 and 61, as indicated at 91, and have mounted thereon gripping teeth 92 which are adapted to engage and penetrate the side and end walls 3 and 5 of the enclosure. A toggle joint 93 comprises a pair of pivotally connected toggle links 94 and 95 the former of which has its outer end pivotally connected to the free end portion of the member 89, and the latter of which has its outer end pivotally secured to the bar element 60. The link 94 is provided at its inner end with a stop lug 96 which permits relative swinging movement between the links 94 and 95 to a point slightly beyond dead center relationship. As shown, when the toggle links 94 and 95 are in their angularly disposed relationship of Fig. 11, the teeth 92 on the member 89 are in a retracted position with respect to their cooperating bar element 60; and when said toggle links 94 and 95 are moved to their opposite extreme position of Fig. 12, the teeth 92 of the member 89 are moved to their extended anchoring position wherein the plate-like member 89 lies against the end wall 5 of the enclosure. The plate-like member 90 and its cooperating bar element 61 are likewise connected by a toggle joint 97 which is identical to the toggle joint 90 and which comprises cooperating toggle links 98 and 99, the former of which is provided with a stop lug 100. The operation of the toggle joint 97 is identical to that of the toggle joint 93 and operates to cause penetration of the teeth 92 into the side wall 3 of the enclosure. A pair of coil tension springs 101 are connected one each between one of the bar elements 60 and 61 and its respective cooperating toothed plate-like member 89 and 90, whereby to yieldingly bias the gripping teeth in the direction of their retracted positions.

40 A pulley mounting cable 36' is connected at one end to the pivotal connection between the links 94 and 95 of the toggle joint 93 by means of a link 102, and at its other end to the pivotal connection between the links 98 and 99 of the toggle joint 97 by a link 103.

45 The form of the invention shown in Figs. 11 to 14 inclusive is placed in desired position in the inside corner defined by the walls 3 and 5 of the enclosure, and the screw 78 rotated until the hinged ends 91 of the members 89 and 90 make contact with their respective walls 5 and 3. At this point it will be noted that the gripping teeth 92 have penetrated sufficiently into the walls of the enclosure to support the device and to exert nominal resistance to a load placed upon the pulley mounting cable 36'. The tail sheave 12 is mounted on the cable 36' as described in connection with the foregoing forms of the invention illustrated. Then when a load is applied to the tail sheave 12 and cable 36', the toggle joints 90 and 97 are moved toward their positions of Fig. 12. Obviously as the load increases, the teeth 92 penetrate further into the walls until the toggle joints 90 and 97 reach their extreme tooth extending positions of Fig. 12. Release of the device of Figs. 11 to 14 inclusive is accomplished by rotating the threaded shaft 78 in a direction to impart movement of the bar elements 60 and 61 in directions causing shortening of the device. If desired, the toggle joints 90 and 97 may be manually moved to their positions of Fig. 11 when the cable 36' has been relieved of its load, thereby reducing the amount of turning of the threaded shaft 78 necessary to remove the device.

70 My invention has been thoroughly tested and found to be completely satisfactory for the accomplishment of the objectives set forth; and while I have shown and described a preferred embodiment of my novel pulley sup-

porting device and two modifications thereof, it will be understood that the same is capable of further modification without departure from the spirit and scope of the invention as defined in the claims.

What I claim is:

1. A manually settable and releasable corner anchor for pulleys and the like comprising a pair of interconnected bar elements extensible between outer end portions thereof for relative expanding and contracting movements of said anchor, primary operating means at the inner end portion of one of said bar elements for setting and releasing movements, a wall gripping tooth portion mounted on the outer end of one bar element, a third bar element connected to the outer end portion of the other of said pair of interconnected bar elements for relative expanding and contracting movements thereof and having a wall gripping tooth portion, actuating means interconnecting said third bar element and one of the first two bar elements and a pulley mounting device having end portions connected respectively to one of said bar elements and to said actuating means and operative under load to cause movement of said third bar element in a direction to increase wall gripping action of its tooth portion.

2. The structure defined in claim 1 in which said teeth provide relatively wide surface portions adapted to face generally in the direction of the load applied to said pulley mounting device, and sharp edge portions in opposition to said relatively wide surfaces, said surfaces and edge portions tapering to points at the outer ends of said teeth.

3. A releasable corner anchoring device for pulleys and the like comprising, a pair of cooperating bar elements, pivot means connecting the bar elements for relative movements producing elongation and shortening of the device, opposed outwardly extending gripping teeth operatively associated with said bar elements and adapted to engage and penetrate adjacent angularly disposed inside corner forming wall portions of an enclosure upon relative elongating movement of said bar elements, means mounting and guiding one of said teeth for independent extending and retracting movements with respect to its associated bar element, lever means for imparting said independent extending movements to said movable tooth, and a pulley mounting device connected to said lever means and operative to move said lever means in a tooth extending direction to cause further penetration of said teeth into said enclosure wall portions responsive to application of a load to said pulley mounting device.

4. A releasable corner anchoring device for pulleys and the like comprising, a pair of cooperating bar elements, means pivotally connecting said bar elements together for relative swinging movements between angularly disposed relationship and generally parallel relationship to provide shortening and elongation respectively of the device, opposed outwardly extending gripping teeth operatively associated with said bar elements and adapted to engage and penetrate adjacent angularly disposed inside corner forming wall portions of an enclosure upon relative elongating movement of said bar elements, one of said teeth being mounted on its associated bar element for independent extending and retracting movements with respect thereto, lever means for imparting said independent extending movements to said movable tooth, and a pulley mounting device connected to said lever means and operative to move said lever means in a tooth extending direction to cause further penetration of said teeth into said enclosure wall portions responsive to application of a load to said pulley mounting device.

5. A releasable corner anchoring device for pulleys and the like comprising, a pair of cooperating bar elements, means pivotally connecting said bar elements together for relative swinging movements between angularly disposed relationship and generally parallel relationship to provide shortening and elongation respectively of the de-

vice, opposed outwardly extending gripping teeth operatively associated with said bar elements and adapted to engage and penetrate adjacent angularly disposed inside corner forming wall portions of an enclosure upon

5 relative elongating movement of said bar elements, means mounting one of said teeth for telescopic sliding movements between a longitudinally extended position and a retracted position with respect to its associated element, lever means for imparting extending movements to said movable tooth, and a pulley mounting device connected to said lever means and operative to move said lever means in a tooth extending direction to cause further penetration of said teeth into said enclosure wall portions responsive to application of a load to said pulley mounting device.

6. A releasable corner anchoring device for pulleys and the like comprising, first and second bar elements, a longitudinally extending gripping tooth mounted on the outer end portion of said first bar element for extending and retracting movements longitudinally thereof, a second longitudinally outwardly extending gripping tooth rigidly mounted on the outer end of said second bar element, said second bar element being pivotally mounted adjacent its tooth equipped outer end to the inner end of said first bar element for relative swinging movement between one extreme position angularly of said first bar element and another extreme position generally parallel to said first bar element to provide shortening and elongation respectively of said device, said teeth being adapted to engage and penetrate adjacent angularly disposed inside corner forming wall portions of an enclosure upon relative elongating movement of said bar elements, lever means for imparting extending movements to said movable tooth, and a pulley mounting device connected to said lever means and operative to move said lever means in a tooth extending direction to cause further penetration of said teeth into said enclosure wall portions responsive to application of a load to said pulley mounting device.

7. A releasable corner anchoring device for pulleys and the like comprising, first and second bar elements, a longitudinally extending gripping tooth mounted on the outer end portion of said first bar element for extending and retracting movements longitudinally thereof, a second longitudinally outwardly extending gripping tooth rigidly mounted on the outer end of said second bar element, means connecting the bar elements for relative movements producing elongation and shortening of the device, said teeth being adapted to engage and penetrate adjacent angularly disposed inside corner forming wall portions of an enclosure upon relative elongating movement of said bar elements, a lever operatively engaging said movable tooth and fulcrumed on said first bar element, and a pulley mounting device secured at opposite ends to said lever and said second bar element longitudinally outwardly of the connecting means therebetween and said first bar element and operative to move said lever in a tooth extending direction to cause further penetration of said teeth into said enclosure wall portions responsive to application of a load to said pulley mounting device.

8. A releasable corner anchoring device for pulleys and the like comprising, first and second bar elements, a longitudinally extending gripping tooth mounted on the outer end portion of said first bar element for extending and retracting movements longitudinally thereof, a second longitudinally outwardly extending gripping tooth rigidly mounted on the outer end of said second bar element, said second bar element being pivotally mounted adjacent its tooth equipped outer end to the inner end of said first bar element for relative swinging movement between one extreme position angularly of said first bar element and another extreme position generally parallel to said first bar element to provide shortening and elongation respectively of said device, said teeth being adapted to engage and penetrate adjacent angularly disposed inside corner

forming wall portions of an enclosure upon relative elongating movement of said bar elements, a lever fulcrumed on said first bar element and operatively engaging said movable gripping tooth, and a pulley mounting device secured at one end to said lever and at its other end to said second bar element longitudinally outwardly of its pivotal connection with said first bar element and operative to move said lever in a tooth extending direction to cause further penetration of said teeth into said enclosure wall portions responsive to application of a load to said pulley mounting device.

9. A releasable corner anchoring device for pulleys and the like comprising, an elongated tubular bar element, a longitudinally extending gripping tooth, means in the outer end of said bar element mounting and guiding said tooth element for extending and retracting movements longitudinally of said bar element, a second bar element, means mounting said second bar element adjacent its outer end to the inner end portion of said first mentioned bar element for relative swinging movements producing elongation and shortening of the device, a second longitudinally outwardly extending gripping tooth rigidly mounted on the outer end of said second bar element, said teeth being adapted to engage and penetrate adjacent angularly disposed inside corner forming wall portions of an enclosure upon relative elongating movement of said bar elements, said first mentioned bar element having a longitudinally extending slot defining a fulcrum, a lever extending through said slot and operatively engaging said movable tooth within said first mentioned bar element and said fulcrum, and a pulley mounting device connected at one end to said lever and at its other end to said second bar element intermediate its outer end and the pivotal mounting means and operative to move said lever in a tooth extending direction to cause further penetration of said teeth into said enclosure wall portions responsive to application of a load to said pulley mounting device.

10. The structure defined in claim 9 in which said pulley mounting means comprises a flexible cable having a length greater than the maximum distance between said lever and the outer end of said second bar element.

11. The structure defined in claim 9 in which said teeth provide relatively wide surface portions adapted to face generally in the direction of the load applied to said pulley mounting device, and sharp edge portions in opposition to said relatively wide surfaces, said surfaces and edge portions tapering to points at the outer ends of said teeth.

12. The device according to claim 1 wherein said actuating means comprises a toggle joint comprising a pair of pivotally connected toggle arms the free end of one of which is pivotally connected to one of said bar elements and the free end of the other of which is pivotally connected to the movable gripping tooth on said third bar element, and a pulley mounting device secured to said toggle joint and extending in a direction wherein a load applied thereto will impart extending movement to said movable gripping tooth to cause further penetration of said teeth into said enclosure wall portions.

13. The device according to claim 1 wherein the actuating means comprises a toggle joint comprising a pair of pivotally connected toggle arms the free end of one of which is pivotally connected to one of said first mentioned bar elements and the free end of the other of which is pivotally connected to the movable gripping tooth on said third bar element and a pulley mounting device secured to said toggle joint and extending in a direction wherein a load applied thereto will impart extending movement of said movable gripping tooth to cause further penetration of said teeth into said enclosure wall portions.

14. The structure defined in claim 13 in which said toggle joint is movable in a plane parallel to the plane of swinging movement of said primary operating means.

15. The structure defined in claim 13 in which said movable tooth includes an elongated tubular sleeve tele-

scopically receiving said third bar element.

16. The structure defined in claim 1 wherein the actuating means comprises a toggle joint comprising a pair of pivotally connected toggle arms the free end of one of which is pivotally connected to said first bar element and the free end of the other of which is pivotally connected to the movable gripping tooth portion on said third bar element, said toggle joint being movable in a horizontal plane to extend and retract said movable gripping tooth, a pulley mounting device comprising a drawbar connected to said toggle joint and extending transversely of said first bar element, whereby a load applied to said drawbar will impart movement to said toggle joint in a tooth extending direction to cause further penetration of said gripping teeth into said enclosure wall portions, and means on said first bar element permitting swinging movements of said drawbar in a horizontal plane and restraining said drawbar against movements in a vertical plane.

17. The structure defined in claim 16 in further combination with means for releasably locking said interconnected bar element in parallel relationship.

18. The structure defined in claim 1 in which the means for interconnecting said bar elements comprises opposed toggle joints pivotally connected at their opposite ends to said bar elements and in further combination with mechanism operatively associated with both of said toggle joints for imparting simultaneous expanding and retracting movements thereto.

19. The structure according to claim 1 wherein said first mentioned gripping tooth portion is movable relative to its bar element, and including additional actuating means for said first mentioned gripping tooth portion.

20. The structure defined in claim 19 in which said actuating means and said additional actuating means comprises a pair of toggle joints one each operatively associated with each of said bar elements and a cooperating gripping tooth, said toggle joints being movable between extreme tooth retracted positions and dead center relationship wherein said gripping teeth are fully extended.

21. The structure defined in claim 20 in further combination with stop means limiting movement of said last mentioned toggle joints in a tooth extending direction, the limit of said movement being slightly over dead center relationship of said toggle joints.

22. The structure defined in claim 21 in further combination with yielding means urging said tooth mounting means in a tooth retracting direction.
